UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 29,312, dated September 6, 1898.

Application filed August 9, 1898. Serial No. 688,217. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part thereof, in which—

Figure 1 is a top or plan view of a manhole-cover, showing the particular shape or configuration of the cover of my said design; and Fig. 2 is an elevational view, partly in section, of the said cover on the line $x-x$ of Fig. 1.

The leading feature of my design consists of the unitary structure made the subject of illustration and having the particular shape or configuration shown and hereinafter described.

In the drawings, a is the cover, which is substantially dish shape in cross - section and having a base or bottom b , upwardly or convexly bent inward. The base or bottom b of

the cover is offset at b' and merges into a surrounding wall or rim c , on the top surface of which concentric grooves or recesses d are provided, as fully illustrated in Fig. 1. In the periphery of the wall or rim c are provided recesses e at suitable distances apart around said wall or rim and tapering gradually from top to bottom of the said wall or rim, as fully illustrated in Fig. 2.

f is a semicircular lug made flat on top and which is curved at and to the base of the same, as illustrated in Fig. 2 of the drawings.

Having thus described my invention, what I claim as new, and desire to secure by Letters Patent, is—

The design for a manhole-cover, substantially as shown and described.

In testimony whereof I have hereunto set my signature in the presence of two subscribing witnesses.

THOMAS P. GREGER.
